METHOD OF FLUSHING.

1,284,180.

Specification of Letters Patent.

Patented Nov. 5, 1918.

Application filed December 26, 1916. Serial No. 138,994.

To all whom it may concern:

Be it known that I, HARRISON TAYLOR CRONK, a citizen of the United States, and resident of the city, county, and State of 5 New York, have invented certain new and useful Improvements in Methods of Flushing, of which the following is a specification.

My invention relates in general to a mechanical method of moving refuse hydraulically along a surface and specifically relates to a method of flushing a water closet bowl. In general, assuming that there is a water supply having a definite force available for refuse flushing purposes it is of importance 10 in many operations to utilize this force economically with the least possible loss of water.

Accordingly one of the objects of the invention is to flush a surface of its refuse 20 matter with an amount of flushing liquid relatively small compared to the mass of refuse to be moved and to thus effect an economy in the use of liquid wherever such flushings are used.

In order to define the basic principle underlying the action of the forces utilized to effect the objects desired attention is called 25 to the situation where a stream of water falls perpendicularly onto a flat surface, such, for instance, as the water falling in the kitchen sink from the faucet. This water forms a thin circular film or skin-like covering which extends radially from the point of contact of the falling stream on to the 30 surface and the circular area of this skin or film is outlined by an irregular wave formation or rather a fringe of broken water particles which have no definite direction of movement and accordingly no readily available force component.

All other conditions being equal and considering that the water strikes the surface normal to its plane, it is obvious that the 35 diameter of this film of water which closely adheres to the surface is directly proportionate to the force of the falling stream. This is a general observation but it is not generally known that this flat skin of water possesses not only a strong propelling force 40 in its directions of flow radially but it also possesses a power to elevate, to plow under, or rather, to slice under a mass of material

having a weight and inertia considerably greater than the mass of water acting on the material. This action of the water film 55 eventually compels the obstructing mass of refuse or other material to move in the direction of movement of the water film acting thereon; the water film acting as a cradle or sledge for the moving mass. Considered in 60 another aspect, the water film may be regarded as a lubricant in which the bottom layer engages the receiving surface, the top layer supports the moving mass and the intermediate layer or portion constitutes the 65 real lubricant or relatively moving particles.

I propose to utilize this powerful skin action but to conserve, direct and control the force of this water skin action that it may have a definite directional flow, so as to get 70 from the force in a limited amount of water, its maximum sweeping effect before it is broken up into its force dissipating fringe.

One means for effecting this economy in 75 use of the water is to eliminate those portions of the stream which are not definitely concerned in its required hydro-dynamic action, or perhaps stating it more definitely, to direct the water, the force of which would otherwise be wasted into that portion of the 80 stream which will do effective work. Accordingly, instead of directing the stream to fall onto the receiving surface perpendicularly thereto as previously considered, the stream may be directed tangentially on to 85 the surface. As the direction of fall moves from the perpendicular direction toward a line paralleling the plane of the surface, the water skin area will tend to distort from its circular form and will approach an elliptical 90 or rather an egg-shape configuration with but small lateral movement. In this way the given force inherent in the falling water instead of spreading over portions of the 95 area not occupied by the matter to be moved, is directed along a relatively long line so that practically the entire available force is directed against the matter disposed in the path of the moving water film. In a crude aspect of the invention this may be attained 100 by directing the water in a single stream at a low angle onto the refuse supporting surface slightly in rear of the mass of refuse to be moved.

A better result is attained, however, if two streams forming an angle of less than 180° with the apex of the angle at, or preferably in rear of the base of the refuse to be moved, is directed onto the surface. Keeping the streams separated until they have almost reached the object to be moved has the effect of conserving the pressure energy of each stream until it can act on the object.

- 10 This method, as thus far outlined might be practised by two persons provided with a couple of buckets of water who would stoop close to the ground and simultaneously eject the contents of the buckets tangentially onto 15 the surface at a point slightly in rear of the refuse. While the method might be thus crudely practised the real economy in operation is effected by practising the method with instrumentalities which will permit of 20 a definite locating of the stream directing means and a definite control of the pressure and character of the ejected streams.

The process is best practised by locating two nozzles, water ejectors or simply fluid outlets, arranged to direct their streams in 25 the form of broad flat shots of water converging at an angle of about 30° to each other, and under a pressure sufficient to cause the refuse matter acted upon to move the 30 requisite distance along the surface before the force of the united stream has been dissipated. It must be emphasized that the water is ejected in the form of liquid shots of short duration but under high pressure. A 35 quiet flowing continuous stream, such as is usual with the flush out types of toilet bowls is of no value in solving the problem of economy in the amount of flushing fluid necessary to propel the refuse matter. The 40 effect of this action is to cause the streams to meet and when viewed in plan, the central portions of the united streams will be seen to have lost their lateral movements to a large extent and the center of the united stream 45 will be somewhat deeper than the outer edges of the united stream and deeper than each of the composite streams. The united stream takes it forwardly projected course along the general resultant direction of movement 50 and acts on the object to be moved, first, by raising a miniature opening under the same and then forcing its way completely under the object to entirely raise the same, even though it may possess some material weight.

55 As the object continues to resist the water force it dams up behind the object and the perpendicular wall of water continues to exert its hydro-dynamic force as the water walls up until the perpendicular weight of 60 the water plus the acquired water pressure horizontally forces the mass in the direction of least resistance, said resistance being minimized by the under layer of water acting as a cradle or sledge.

65 Obviously, the smaller the angle between

the ejected streams, the greater will be the propelling force of the united stream but with a unilateral stream there will be more of a pushing or flooding effect of a moving body of water rather than the forceful lifting effect of a skin of water which is one of the features of this invention.

If a slight resistance is offered to the free flow of the stream at a point at or in advance of the object or mass to be moved a moving 70 wall of water will be formed momentarily having a velocity slightly less than the velocity of the succeeding portion and a relatively high column of water is formed in rear of the refuse to enhance the lifting 75 effect of the skin action.

Further the invention contemplates the use of a stream in addition to the two streams described. This third stream is directed to flow in the same general direction 80 as the resultant direction of flow of the two angled streams.

The invention has thus far been described without reference to the character of the refuse receiving surface and as a matter of 90 fact the surface may be flat or channel shape. As the primary object of the invention, however, is to effect an economy in the use of the flushing liquid the refuse receiving surface preferably should be designed 95 to assist in the conservation of the force of the liquid directed thereto. One means for effecting this object is to wall off the circular skin portion hereinbefore described with reference to the water falling into the sink so 100 as to eliminate splatter and to confine the length of refuse receiving surface to the radius of the circular skin portion. In this way the area of the surface acted upon is limited and of course the amount of necessary water is minimized.

This water skin has another aspect. It has been noted that when the vertically falling stream strikes a surface which can be worn away as when water from the 110 leaders of a house strike soft ground a depression is formed which merges into a series of troughs, each of less depth than the preceding trough. Considering the first depression it is found that any foreign 115 matter, such as sand is quickly swept therefrom by the falling water. It has been found experimentally that by using a refuse receiving surface having a long sweeping curve trough as suggested and directing the 120 two streams as defined longitudinally along such a surface the most perfected method of flushing has been attained. With a variation in the mass of the refuse to be moved, ordinarily a slight increase in the mass of 125 water comprising the shots should be made but it is of more importance, when possible, to increase the pressure acting on the shots to the point necessary to move the refuse the desired distance. Where the normal mass to 130

be moved is constant and where the water pressure is also constant as where the water is supplied through a suitable flushometer from the city water supply, then the water 5 ejecting nozzles may be fixed in place.

The method has been developed as a flushing operation finding its commercial adaptability in washing off open sewers, urinals and water closet bowls but these devices are 10 merely suggestive of the places where such a method may be practised.

One set of instrumentalities by means of which the process herein disclosed may be practised is illustrated in the accompanying 15 drawings, in which—

Figure 1 is a side elevation of an arrangement of liquid ejecting devices, acting upon a mass of refuse which is desired to be moved;

Fig. 2 is a plan view looking down upon the arrangement shown in Fig. 1 and after the water shots have struck the surface; and

Fig. 3 is a longitudinal sectional view 25 through a portion of a flushed surface while a water shot is spreading over the surface.

In the drawing there is shown a mass of refuse 3 mounted upon a supporting surface 4 which may be considered as horizontally disposed or, to illustrate a further refinement of the process, may be inclined upwardly at a slight angle to the horizontal. A pair of liquid ejecting devices 5 and 6 in the form of guns are so disposed to the 30 rear of the refuse and with their nozzles so directed that the shots of water W or other liquid passed therefrom are designed to pass the same along converging paths forming an angle of less than 180° as indicated by the dotted lines. The shots of liquid meet the surface at or preferably just in rear of the base of the mass of refuse to be moved. It is merely required that these 35 two guns be disposed above the surface 4, it being understood that the inclination of the nozzles toward the surface, the inclination toward each other and the force with which the liquid shots are projected will, obviously, depend upon the character of the 40 surface to be flushed, upon the character and mass of refuse to be moved and upon the direction in which it is desired to move the refuse. To illustrate a further refinement of the method it may be considered 45 that the nozzles of the guns are designed to eject the shots in the form of a flat bolt substantially rectangular in cross-section.

In order to show the disposition of a means for forming a third stream or rather 50 shot of liquid having the same general direction of movement as the resultant direction of flow of the two angled streams previously mentioned, a third liquid ejecting means 7 in the form of a gun is shown in 55 position to direct its shot in the general line

of resultant movement of the mass when moved along its surface by the guns 5 and 6.

The guns are shown to be in the form of manually actuated syringes, so as to illustrate the possibility of obtaining a variable 70 ejecting force which will be dependent upon the pressure and velocity of movement of the ejecting handle 8. It is quite obvious that where the conditions of repeated use remain the same, some constant ejecting 75 force may be substituted for the variable pressure inherent in the manual actuation of the mechanisms illustrated and some automatically actuated measuring device such as a flushometer may be used in place of 80 the syringes illustrated. In general the character of instrumentalities utilized to practice the method will depend upon the purpose for which the method is utilized.

In operation, the guns 5 and 6 are pointed 85 toward the base of the mass of refuse so as to direct the charges from the guns in the general direction in which it is desired to cause the refuse to be moved. If more of a propelling than a lifting force on the 90 refuse is desired, then the nozzles are lowered toward the surface to be flushed and into a position extending substantially parallel to the surface and conversely the rear ends of the nozzles are raised from the position shown in Fig. 1 so as to depend if it is the lifting force which is particularly desired. Should it be desired to effect a combined lifting and turning movement of 95 the refuse, then one of the guns is positioned at a higher level than the other. As economy in amount of liquid used is the primary consideration, then in cases where a heavy mass of refuse is to be moved with the same mass of liquid shot used with a 100 relatively lighter mass of refuse, a greater ejecting pressure must be imposed on the relatively light mass of liquid shot. If the total available force is insufficient to effect 105 the desired movement of the mass of refuse, then obviously an increase in the mass of propelling liquid must be made in order to obtain the momentum (mass times acceleration) necessary to effect the desired movement of the refuse. In the organization 110 illustrated this increase in liquid mass may be effected by increasing the charge of liquid drawn into the syringes or by using larger size syringes.

In some situations, as on railroad cars, 115 there is available a source of high pressure as in the exhaust steam line, but the available amount of flushing liquid is usually limited and therefore it is sometimes quite economical to use very high pressure on a 120 small mass of liquid. If this small mass of liquid is projected at high velocity and care is taken to direct the same so as to utilize the skin effect to elevate the refuse, a relatively large mass of refuse may be 125 130

propelled even with a small amount of flushing liquid.

In order to obtain the most effective propelling results, care must be taken that there be no obstructing forces present.

When it is necessary to receive the refuse in a liquid pool of any kind, this pool should be of the least possible depth and mass for it tends to block the action of the flushing 10 shots before they can reach the mass to be moved and thus reduces the efficiency of the method.

Having thus described my invention, I claim:

15 1. In the art of flushing hydraulically, the method which consists in directing two streams of water toward the refuse matter to be flushed and along paths converging toward each other laterally of the general 20 resultant direction of movement of the two streams when united, whereby portions of the streams will meet adjacent the refuse matter and tend to lift the refuse matter as it is swept in the general resultant direction 25 of movement, causing said refuse matter to be subjected to the action of a third stream of water moving in the general resultant direction of flow, offering slight resistance to the free flow of said refuse and 30 water whereby a moving wall of water will be formed having a velocity slightly less than the velocity of the succeeding portions of said united streams thereby to cause the accumulation of a wall of water having a 35 hydro-dynamic force sufficient to move the mass of refuse with the least possible amount of water.

2. In the art of moving a body of refuse along a refuse receiving surface, the method 40 which consists in directing a small portion of liquid suddenly and forcibly onto the surface at a relatively low angle thereto and contacting therewith at a point slightly in rear of the base of the body of refuse to be 45 moved, said small portion of liquid having a mass less than the mass of refuse to be moved and having a pressure sufficient to cause the skin of liquid thus formed on the surface to slide in under the body of refuse and to lift the same into the resulting moving 50 stream.

3. In the art of flushing refuse matter along a refuse receiving surface, the method which consists in directing a pair of streams 55 of water toward the refuse matter at an angle less than 180° relative to each other and at an angle less than 45° to the surface thereby to cause the streams to meet adjacent the refuse matter to raise the same into 60 the main stream formed by the union of the pair of streams.

4. In the art of flushing a surface of a mass of refuse matter, the method which consists in directing two streams of water 65 toward the refuse matter to be flushed and

toward each other laterally of the general resultant direction of movement of the two streams when united whereby portions of the streams will meet adjacent the refuse matter and coact to raise the same off the 70 surface as the refuse matter is swept in the general resultant direction of movement of the united streams.

5. In the art of flushing a surface of a mass of refuse disposed thereon, the method 75 which consists in directing a plurality of fluid streams toward one side of the base of said refuse mass with certain of said streams forming an acute angle with each other whereby the meeting streams will act 80 on the refuse mass to raise the same off said surface and to move the same along said surface.

6. In the art of flushing a surface of a body with refuse disposed thereon, the method 85 which consists in directing a pair of fluid streams toward said refuse, said streams meeting at a point in rear of the body of refuse and at an angle to each other and directing a third stream toward said refuse and along a line substantially bisecting the angle 90 formed by said first named pairs of streams.

7. In the art of flushing a surface of a body of refuse disposed thereon, the method which consists in directing a pair of fluid streams toward said refuse, said streams meeting at a point in rear of the body of 95 refuse and at an angle to each other and directing a third stream toward said refuse and along a line substantially bisecting the angle formed by said first named pairs of streams.

8. In the art of flushing a surface of a 100 body of refuse disposed thereon, the method which consists in simultaneously subjecting opposite or substantially opposite sides of the refuse body adjacent its bottom with a fluid pressure means comprising a plurality 105 of separate liquid shots, each having a relatively small mass and acting on the refuse along lines forming angles less than 45° to the surface, thereby to raise the refuse off said surface.

9. In the art of flushing a surface of a mass of refuse thereon, the method which consists in directing a shot of liquid on to said surface at a point adjacent the mass, in a direction toward said mass and at an 115 angle to the surface less than 90° , said shot of liquid having a mass less than the mass of the refuse to be moved and having a force sufficient to move the mass of refuse.

10. In the art of flushing a surface of a 120 mass of refuse thereon, the method which consists in projecting a liquid shot downwardly and forwardly onto said surface adjacent one side of the mass to be moved, said shot having a mass less than the mass of 125 said refuse.

11. In the art of flushing a surface of a mass of refuse thereon, the method which consists in projecting a liquid shot downwardly and forwardly onto said surface 130

adjacent one side of the mass to be moved, said shot having a mass less than the mass of said refuse and subjecting said liquid shot to a relatively high propelling force where-
5 by the relatively small mass constituting the liquid shot will possess relatively high pro-
pelling momentum.

Signed at New York city in the county of New York and State of New York this 28th day of November, A. D. 1916.
